UNITED STATES PATENT OFFICE.

EDMUND A. USINA, OF NEWTONVILLE, MASSACHUSETTS.

MANUFACTURE OF BELTING.

No. 853,567.

Specification of Letters Patent.

Patented May 14, 1907.

Application filed November 29, 1905. Serial No. 289,699.

To all whom it may concern:

Be it known that I, EDMUND A. USINA, a citizen of the United States, residing at Newtonville, in the county of Middlesex and State of Massachusetts, have invented certain new and useful Improvements in the Manufacture of Belting, of which the following is a specification.

This invention aims to provide an improved method of manufacturing belting which avoids much of the expense involved in the present method of manufacture, and many of the disadvantages inherent in the style of belting now generally used.

The invention applies more particularly to leather belting of the style used in driving machinery, and the like, though it is not limited thereto.

In ordinary leather belting the hides are cut into strips of the width of the belting and the ends are lapped and, ordinarily, cemented together. The strips can never be more than about six feet long. The lapped ends of the strip have to be carefully tapered off by hand. The amount of lap is ordinarily equal to the width of the belt, so that in 12-inch belting the effective length of the sections is only about five feet. There has not yet been found a cement which will stand the continual bending and pulling strain to which the lap is subjected, especially in damp situations such as dye houses or breweries. Various expedients have been resorted to in order to overcome this difficulty. Metallic fasteners instead of cemented ends, and link belting formed of short oblong pieces of leather arranged on edge, have been used to some extent, but have not superseded the lapped and cemented belts.

According to this invention a plurality of sheets of the belting material are united, and the belting then cut from the united sheets. Preferably the sheets are fastened together, as by cementing, as they are piled one upon another, and belting cut off from the pile by a knife or saw or other cutting tool, which passes through the pile and cuts in any desired direction, the product being made up of pieces of the belting material fastened together with their cut edges forming the faces of the belting. The path along which the cutting tool progresses may be spiral or back and forth in any desired directions, so as to cut from the pile strips which are very much longer than the length of the pile or of the

individual sheets of material (hides in the case of leather belting). Preferably cement is used to fasten the sheets together, as it acts firmly at all points of the sheet, and puts no limitations upon the cutting tool as to its direction or the manner of use. Cement is sufficient for such a belting, in which the joints run lengthwise of the belt, so that they are subject to no appreciable lengthwise strain. Preferably for leather belting only the fleshy portion of the hides is used. The outer side of the hides can be split off and possesses a higher value because of its finish, whereas the fleshy side has the greater strength and is better adapted for use in belts. Since by this method of manufacture the thickness of the belt is dependent only on the width of the individual strips of which it is composed, the removal of the outer smooth side of the hide lessens the cost of the material, and at the same time produces a stronger belt.

A great advantage of the process is in the possibility of making belts of any desired thickness, the only difference in cost being in the quantity of material used.

The work may be expedited by using a gang of cutters instead of a single cutter. In order to make belts of any desired length with one straight cut, the sheets may be arranged in a long pile, successive sheets of any particular layer being arranged end to end, with their ends overlapping, and the joints in the successive layers being broken. When such a continuous pile is formed and a strip of belting is cut therefrom, the belting will be formed of strips as in the original case discussed above, but jointed, the joints of adjacent strips being staggered.

Other features of advantage are referred to in detail hereinafter.

The accompanying drawings illustrate an embodiment of the invention.

Figures 1 and 2 are plans, and Fig. 3 a longitudinal section of a pile of hides; Fig. 4 is a perspective view of a piece of belting cut therefrom; Fig. 5 is a similar view of an endless belt which may also be made by this process; Fig. 6 is a transverse section of the belting on a larger scale; Fig. 7 is a perspective of an alternative manner of uniting two ends of a belt.

Referring to the embodiment of the invention illustrated, a number of hides A, either complete or with the outer portions removed

so as to leave only the fleshy side, are formed into a pile B, the depth corresponding to the width of the belting desired. Cement is distributed thoroughly between the successive hides. Preferably the sheets are pressed together so as to cause a firm cementing thereof. When the successive hides are firmly united, or while they are held together in a press, the belting is cut therefrom, as for example by means of a knife or saw or other cutting tool C, which progresses in the direction of the arrow in Figs. 1 and 2. For the purpose of obtaining a belt longer than the individual hides, the cutting tool C may travel back and forth in any desired manner. For example the belt may be cut from the pile in approximately a spiral, as shown in Fig. 1. The length may be practically anything desired, or the belting may be made in a single continuous strip which shall use up the entire pile of hides, and may then be cut off into lengths to suit. Fig. 4 shows a finished belt D without transverse joints between its ends. The ends E may be cut on a taper as shown, by the cutting tool, and may be cemented or fastened with metallic fasteners or otherwise. Thus instead of a number of transverse joints, the belt will have only a single such joint. Or a belt such as F (Fig. 3) may be produced by suitably directing the cutting tool C to cut first the outer periphery forming a closed figure, and afterward the inner periphery parallel thereto. Obviously such a belt may be made more than twice as long as the hide, and by introducing convolutions in the path of movement of the cutting tool, the length of the belt may be extended indefinitely. This capacity for making a belt which shall be absolutely endless and without transverse joints, marks in my opinion an immense advance in the art.

In the enlarged view, Fig. 6, are shown more clearly the edges G of the individual strips or pieces H of material forming the faces of the belt and, by a heavy line, the cement J between the successive strips. The width of the several pieces H constituting the belting, will depend upon the thicknesses of the original sheets. They are not necessarily the same. Any sound stock may be used, either of whole hides or the fleshy portion of split hides, or of any combination thereof. For example, the end pieces H' may have on their outer faces the smooth side of the hide, while all the intermediate pieces may be made solely of the fleshy portion of the hide. The thickness of the belt and its flexibility depend upon the widths of the individual pieces H.

In the manufacture of belts by the ordinary method, not more than 50 per cent of the hide can be used. By the present method it is possible to utilize 75 per cent or more of each hide. At the same time the new belt is 65 cheaper as well as more durable than the old.

The cut edges of the hide can be finished to have the same appearance as the surface of the leather if desired.

By the term "cutting" as used herein, I mean to include the dividing of the material by any suitable means. There are several styles of leather working machinery which can be used for the purpose. In the term "belting" I mean to include any article made of pieces of belting material fastened together with cut edges forming a face of the article.

Fig. 2 illustrates the use of a gang of cutters C moving together and cutting a number of pieces of belting at once. This figure, in connection with Fig. 3, also shows the manner of piling the sheets to secure pieces of belting of any desired length. The lower layer of sheets A' are jointed transversely of the pile, as at K'. The next layer is similarly jointed, the joints being staggered relatively to the lower layer. The joints K, K' &c., extend transversely across the sheets, and are preferably beveled and overlapped and cemented.

Instead of the beveled and cemented ends E indicated in Fig. 4, the connection between the ends of the belt may be made by a series of tongues L (Fig. 7) extending from one end of the belt into the grooves formed by tongues L' from the opposite end. The parts may be cemented together or fastened with metallic fasteners.

Therefore though I have described with great particularity of detail certain specific embodiments of the invention, it is not to be understood that the invention is limited to the specific process described. Various modifications thereof in detail and in the arrangement and combination of the parts, may be made by those skilled in the art, without departure from the invention.

What I claim is:—

1. The process of manufacturing leather belting which consists in laying a number of hides and cementing them one upon another over substantially their entire area to form a pile of hides cemented together and cutting therefrom portions of a width corresponding to the depth of the pile and of a thickness corresponding to the distance between successive cuts and suitable to produce a substantial flexibility whereby a flexible belt is produced composed of adjacent longitudinal strips already cemented together.

2. The process of manufacturing leather belting which consists in laying a number of sheets of the fleshy portion of hides and cementing them one upon another over substantially their entire area to form a pile of hides cemented together and cutting therefrom portions of a width corresponding to the depth of the pile and of a thickness corresponding to the distance between successive cuts and suitable to produce a substan-

tial flexibility whereby a flexible belt is produced composed of adjacent longitudinal strips already cemented together.

3. The process of manufacturing belting which consists in uniting a plurality of sheets end to end in a layer, superposing a number of such layers upon each other to form a pile, and cutting the belting therefrom with its width corresponding to the depth of the pile, whereby a belt of any desired length may be made with one straight cut.

4. The process of manufacturing belting which consists in uniting a plurality of sheets end to end in a layer, superposing a number of such layers upon each other to form a pile,

the successive sheets in a layer overlapping end to end, and the joints in the successive layers being staggered, and cutting the belting therefrom with its width corresponding to the depth of the pile, whereby a belt of any ²⁰ desired length may be made with one straight cut and with the adjacent strips staggered and each strip having lapped end joints.

In witness whereof, I have hereunto signed my name in the presence of two ²⁵ sub-scribing witnesses.

EDMUND A. USINA.
